BULLET TRAP**Norman D. Marden, Chincoteague, Va., and Robert B. McLaughlin, Washington, D. C.**

Application September 15, 1954, Serial No. 456,341

9 Claims. (Cl. 73—167)

(Granted under Title 35, U. S. Code (1952), sec. 266)

The invention described herein may be manufactured and used by or for the Government of the United States of America for governmental purposes without the payment of any royalties thereon or therefor.

This invention relates to the trapping of bullets, and more particularly to a method and means for dissipating the energy imparted to bullets at the moment of firing, so that their travel will be confined to a very short distance and will terminate in a specific area where recovery of the spent bullets can be effected readily and without inconvenience, waste or damage to the bullets.

An object of the invention is to provide a novel method of decelerating a single bullet, or a burst of several bullets, to prevent bullet travel beyond a predetermined point.

Another object is to provide a bullet trap of novel construction, having means incorporated therewith to control the course of fired bullets, and to cause them to come to rest in a specified area.

Another object is to provide a bullet trap incorporating means facilitating recovery of spent bullets with a minimum of effort.

In the testing of firearms it has been customary to employ means for trapping the bullets discharged by the weapons being tested. In some instances prior art traps have been constructed of bales of straw, sawdust, or banks of sand etc. In other traps a long horizontal conduit has been utilized, the bullets being fired into the conduit simultaneously with the introduction of a compressible mixture of liquid and gas which is caused by large pumps to flow in a vortex along the horizontally placed conduit and thus tend to decelerate the bullet to the velocity of the flowing mixture.

Each of these general types of trap has its disadvantages; the sand type being resistant to ready recovery of the spent bullets, and, when long bursts are attempted, being subject to ricochet and to the creation of clouds of fine dust which are a health hazard. Liquid traps with a flowing compressible mixture are expensive in construction, require large pumps and are complex in structure, maintenance, and operation. In addition, during the firing of a sustained burst, the bullets tend to bore a hole in the liquid thus destroying its stopping power and causing the bullets to strike each other and to tumble in an uncontrolled manner. Neither form of trap appears to be suitable for long sustained bursts of firing.

The present invention provides a new method of bullet trapping, by which the travel of the bullet is confined to a very short path, and in which deceleration is accomplished without resort to complex mechanism such as is required in the constant flow liquid and air method of trapping above described. At the same time the new method disclosed and claimed herein lends itself to ready recovery of the spent bullets without any of the recovery effort involved in the sand bank method of trapping. In addition the construction of the present invention for the first time permits the firing of long bursts of bullets which do not ricochet off of each other and do not bore a hole

2

in the liquid medium so that it loses its projectile controlling qualities.

Accordingly, a further object of the invention is to provide a novel and inexpensive method for decelerating and collecting bullets discharged in relatively long bursts, to permit their recovery without any appreciable effort or damage.

Other objects and many of the attendant advantages of this invention will be readily appreciated as the same becomes better understood by reference to the following detailed description when considered in connection with the accompanying drawings wherein:

Fig. 1 is a longitudinal sectional view of a bullet trap illustrating one embodiment of the present invention;

Fig. 2 is an enlarged sectional view of one form of muzzle blast deflector suitable for use with the present invention;

Fig. 3 is a perspective view of one form of bullet collecting basket for use with the embodiment shown;

Fig. 4 is an enlarged perspective view of one form of trap draining sump suitable for use with the present invention;

Fig. 5 is a top plan view partially in horizontal section of another embodiment of the present invention wherein the trap includes a resiliently supported inner tank;

Fig. 6 is a vertical section of the embodiment illustrated in Fig. 5 taken along a line substantially corresponding to line 6—6 of Fig. 5; and

Fig. 7 is a detail view of a resilient pad suitable for use in absorbing shock waves.

In the embodiment illustrated in Fig. 1 the invention is shown comprising a horizontally disposed roof wall 11, a base room wall 12 which may slope as illustrated, if desired, and side and end room walls 13, 14 and 15. These may be formed of any suitable material such as concrete, and may if desired be lined with an inner layer 16 of sound insulating or other material. Within the chamber thus formed there is provided a basin 17 to which water or other suitable liquid may be supplied by way of one or more supply pipes 18 terminating just inside the rear vertical wall 19 of the basin; said pipes being in turn supplied with water under pressure from any conventional source, not shown. The upper and lower walls 21 and 22 of the basin 17 may be parallel to the upper room wall 11, and at the converging edges of walls 21 and 12 they receive an apertured and pivoted shield 23 adjustably supported by an arm having a turnbuckle 24. This turnbuckle may include a resilient coupling by the use of springs or rubber bushings. A splash shield 27 having sides 26 is mounted as shown. The pivoted shield element 23 has an aperture, as at 28, aligning with the aperture 29 in room wall 13; the latter permitting insertion of the barrel 31 of a gun, or other weapon, adapted to discharge bullets or other missiles into basin 17 by way of aperture 28; the word "bullet" as used herein being intended to embrace any form of weapon discharged missile. It has been determined that the bullets may be fired into the tank of water at angles from 8 to 20° declination depending upon the shape of the bullet, the angle being necessarily greater for more pointed missiles and less for blunt missiles.

In the embodiment illustrated insulation 20 is shown interposed between the room housing the gun and the room housing the tank.

At the lowermost corner of basin 17 is shown provided a wire mesh basket 36 preferably having the general contour shown in Fig. 3, facilitating its reception at the bottom of the basin, and also its ready withdrawal through the forward opening provided by swinging back the pivotal shield 23, when weapon firing has ceased. Below the position occupied by the wire mesh basket may be located a small drain tank 39 (Fig. 4) from which leads a

pipe 41 terminating in a discharge spout 42, in advance of which is a normally closed drain valve 43 operable by turning handwheel 44 disposed at the upper end of the long stem 46. Openings 51 and 52 in the upper concrete wall provide for ventilation and for access and visual inspection and manipulation of the elements 23 and 44.

As bullets are discharged from gun barrel 31, either as single shots or as multiple shot bursts, they pass through the aperture in element 23 and strike the surface of the water in basin 17 at the point indicated at 61, then continue generally down the path indicated generally at 62, the velocity diminishing gradually from point 61, and along path 62, so that sometime before reaching the basket there is no velocity remaining, and they fall to the sloping surface of the bottom. Upon bullet entry into the water some splashing may occur, but shield 27 and the top wall 21 of the basin serve to confine such splashing. It will be noted that the shield 23 serves generally to deflect to stack 35 the pressures created by gases or compressed air in the region adjacent the gun barrel, and the coupling 24 if made resilient serves to cushion the vibrations of shield 23.

In Figs. 5 and 6 there is shown a second embodiment of the present invention wherein the bullet receiving tank may be of the general shape shown in the first embodiment but which is resiliently mounted within and spaced from the concrete floor 12 and end wall 19 by means of suitable springs 41a or other resilient or shock absorbing means whereby the force of the impact of the bullet or bullets upon the body of liquid is absorbed and not transmitted to the adjacent wall. As in the first embodiment a suitable insulating barrier 20 may be interposed between the room containing the tank and the gun test room to isolate the gun from vibrations occurring in the tank room.

As illustrated in Fig. 5 the air supplied through pipes 63 and outlets 64 may be introduced into the tank in a variety of patterns. Thus, the point of introduction of the bullet into the water, indicated generally by the reference character 61, may be surrounded by a curtain of bubbles emerging from a looped conduit 65 embodied in or lying upon the floor of the tank, which bubbles being compressible and present in substantial quantity absorb shock caused by bullet entry into the water. Also a plurality of transversely extending conduits or pipes, perforated as illustrated, may be employed to provide a number of curtains of compressible bubbles extending across the tank and through which curtains the shock waves of the bullets must pass. At the far end of the tank and adjacent the rear wall 19 may be provided an additional transversely extending pipe 66 which in this instance is shown located in the tank outlet sump 39. Bubbles from this pipe provide a protective, absorbent curtain to protect the rear wall from the shock wave.

The tank walls or a portion thereof both above and below the water line may be lined with a resilient cushion 70 of the general character illustrated in Fig. 7 wherein a so-called "unicellular" resilient pad is shown. This pad may be formed of plastic material having a large number of closely arranged independent cells which are discontinuous and impervious to moisture penetration. Since the cells are not interconnected the pad will not become waterlogged. It will be apparent that by providing a lining of this material within the tank 17 such as along the side or back walls thereof a degree of compressibility is provided to absorb shock waves which strike these surfaces. If desired a perforate mesh screen 71 may be provided over such pads.

It will be apparent to those skilled in the art that the shape and disposition of the air emitting muzzles may be varied as desired and that an emulsifying agent may be added to the liquid in order to enhance the bubble retaining characteristics of the liquid.

With either embodiment of the present invention there

is provided a simple and inexpensive means for decelerating and capturing bullets fired from a repeating gun and the effect of firing into the surface of a body of water in the manner illustrated is to individually decelerate each bullet in a burst of bullets, independently of the other bullets in said burst. This occurs because of the action of the water in closing behind a bullet before the succeeding bullet in the burst strikes the surface of the water, hence even the firing of sustain bursts of bullets do not cause a hole to be bored into the water with consequent striking of the bullets against each other at high velocity.

Obviously many modifications and variations of the present invention are possible in the light of the above teachings. It is therefore to be understood that within the scope of the appended claims the invention may be practiced otherwise than as specifically described.

What is claimed is:

1. A bullet trap comprising a basin containing a liquid to receive a bullet, means including a basket withdrawable from the lowermost rear part of the basin through a top forward part of the basin to recover the bullet after firing, means supporting a gun adjacent the forward part of the basin at an oblique angle to the surface of the liquid in the basin, and means covering a major portion of the basin to control liquid splash.

2. A bullet trap comprising an apertured container filled with liquid, an apertured blast deflector pivotally mounted adjacent said container aperture, means for supporting a firearm for firing into said container at a minimum angle of 8° to the surface of the liquid, a protective shield covering the greater portion of the container, and bullet recovery means including a scoop movably mounted adjacent the bottom of said container.

3. A bullet trap comprising a basin containing a liquid to receive a plurality of bullets fired in rapid sequence, mount means adjacent the forward end of the basin, a firearm supported on said mount means at an oblique angle to the horizontal surface of the liquid in the basin, said firearm being positioned to direct the bullet into the basin so that an unimpeded underwater path of substantial length is provided for underwater bullet travel, a blast deflector pivotally and adjustably mounted adjacent said basin and having an aperture therein through which the bullet passes prior to entering the liquid, and means forming a part of said basin and covering a substantial portion thereof for controlling liquid splash upon entrance of the bullet into said liquid.

4. A bullet trap for projectiles comprising; a basin containing a liquid and a stand supporting a firearm having a barrel at an oblique angle to the horizontal surface of the liquid in the basin so that the direct line of fire of the projectiles is at an angle to the surface of the liquid in excess of 8°, and a blast deflector pivotally and adjustably mounted adjacent said basin and having an aperture therein movable in said line of fire of the projectile as the deflector is adjusted with respect to the barrel.

5. A bullet trap comprising: a basin containing a liquid to decelerate a bullet, said basin having side walls, a rear wall, a sloping lower wall and a top wall, said top wall and said lower wall converging forming a forward opening; a basket placed at the lowermost rear part of the basin and withdrawable through said forward opening to recover a bullet after firing; means supporting a gun adjacent the forward opening of the basin at an oblique angle to the surface of the liquid; and means covering a portion of the basin to control liquid splash.

6. A bullet trap as set forth in claim 5, said walls being lined with a cushion of resilient, plastic material of closely arranged independent cells impervious to moisture penetration so that any shock waves, caused by a bullet, are absorbed upon striking the cushion.

7. A trap for decelerating projectiles fired from an inclined firearm comprising; a container having a quantity of liquid and a projectile entrance opening therein, a blast

deflector pivotally and adjustably mounted adjacent said opening and having an aperture therein in alignment with said opening, means supporting a firearm adjacent said opening with the barrel of the firearm at an acute angle with respect to the surface of the liquid and in alignment with said aperture and opening, means forming a part of said container and covering a substantial part of said container for controlling liquid splash after the projectile passes through said aperture and opening and upon entrance thereof into said liquid, and supply means arranged within said container and submerged within said liquid for introducing gas into the liquid and render the liquid sufficiently compressible to absorb the shock as the projectile enters the liquid and to decelerate the forward progress of the projectile as the projectile travels therethrough.

8. A trap for decelerating projectiles fired from a firearm comprising a basin containing a quantity of liquid to receive fired projectiles, means supporting a firearm to fire projectiles into said liquid, means for introducing curtains of gaseous bubbles across the path of underwater travel of the projectiles in a manner to absorb the shock as the projectiles enter the liquid and to decelerate the forward progress of the projectiles as the projectiles travel therethrough, a blast deflector pivotally and adjustably

mounted adjacent one end of the basin and having an aperture therein through which the projectiles pass prior to entering the liquid, and means covering a substantial portion of the basin to control liquid splash as each projectile strikes and enters the liquid.

9. A bullet trap comprising; an apertured container filled with liquid, an apertured blast deflector pivotally mounted adjacent said container aperture, an enclosure for said container, means within the enclosure for supporting a firearm having a gun barrel, and an internal wall on said enclosure and provided with an aperture in alignment with and mutually spaced from said deflector aperture and said container aperture, said aperture in the wall having a gun barrel of a firearm disposed therein and extending therethrough for firing a bullet through said apertured blast deflector into said aperture container at a minimum angle of 8° to the surface of the liquid.
